BUFFING WHEEL

Louis M. Seelenfreund, Chicago, Ill., assignor to
 Action Buffs, Inc., Chicago, Ill., a corporation
 of Illinois

Application May 25, 1948, Serial No. 29,040

2 Claims. (Cl. 51—193)

1

The present invention relates generally to buffing wheels. More particularly the invention relates to that type of buffing wheel which is adapted to be mounted on a power driven shaft by way of a hollow hub structure, serves during drive of the shaft and while a metallic or other surface is placed against its outer periphery to effect polishing or buffing of the surface, and comprises a rectilinear series of side by side buffing sections, each of which consists of a plurality of annular, juxtaposed fabric layers with gathered or pleated inner margins for ventilating purposes, and a metallic ring shaped core for holding the layers together and supporting them with respect to the hollow hub structure.

As evidenced by United States patent application Serial No. 772,800, filed by me on September 8, 1947, it has heretofore been proposed in connection with the fabrication of buffing wheels of the aforementioned type to employ as the core of each buffing section a pair of complementary, preformed, oppositely positioned, rigid rings, each of which is in the form of a one-piece metallic stamping and embodies a cylindrical base flange, an annular outer side flange extending outwards from the outer margin of the base flange, and a circular series of spaced apart, inwardly extending, layer-gripping teeth on the outer margin of the side flange. It has also been proposed to form the base flange of one of the two core-forming rings of each buffing section of slightly less diameter than the base flange of the other ring and to connect together the two rings by pressing them together so that the base flanges are in telescopic relation and grip one another frictionally. In practice it has been found that a buffing wheel as heretofore proposed is subject to the objection that the base flanges of the core-forming rings of the buffing sections cannot be made so as to grip one another frictionally with sufficient force to prevent the rings from spreading or sliding axially apart in response to the outward pressure that is exerted by the pleated inner margins of the fabric layers due to compression.

One object of the invention is to provide a buffing wheel which is an improvement upon, and eliminates the objection to, previously designed buffing wheels of the two-piece core variety and is characterized by the fact that the complementary, oppositely positioned core-forming rings of the buffing sections are positively held against separation by way of annular lips which are connected to, and bent outwards from, the free margins of the small diameter cylindrical base flanges and are arranged in lapped relation with the an-

2

nular side flanges of the rings having the large diameter base flanges.

Another object of the invention is to provide a buffing wheel of the type and character last mentioned in which the annular outwardly bent lips on the free margins of the small diameter base flanges serve, in addition to preventing separation of the core-forming rings, to space the buffing sections apart and have formed therein cutouts or notches whereby air that flows into the hollow hub structure on which the buffing sections are mounted is permitted to flow outwards past the fabric layers and effect cooling thereof.

A further object of the invention is to provide a buffing wheel which is generally of new and improved construction, effectively and efficiently fulfills its intended purpose and, in addition, possesses longer life and is capable of being produced at a comparatively low cost.

Other objects of the invention and the various advantages and characteristics of the present buffing wheel will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is an axial section showing a buffing wheel embodying the invention operatively connected to a power driven shaft by way of a conventional hollow hub structure;

Figure 2 is a fragmentary side elevation of one of the buffing sections of the wheel;

Figure 3 is a plan view showing in separated or dismantled relation a pair of complementary, preformed, rigid rings constituting the core for one of the buffing sections;

Figure 4 is a section showing the core forming rings of Figure 3 before being shifted together into assembled relation with the fabric layers;

Figure 5 is a section showing the core forming rings of Figures 3 and 4 after they have been shifted together into assembled or telescopic relation but before bending outwards the notched annular lip on the free margin of the small diameter cylindrical base flange; and

Figure 6 is an enlarged fragmentary section illustrating in detail the manner in which the notched outwardly extending annular lips constituting parts of the two piece cores of the buffing sections serve to space the sections apart and

also permit cooling air to flow outwards from the hollow hub structure past the fabric layers.

The buffing wheel which is shown in the drawings constitutes the preferred form or embodiment of the invention and is adapted to be mounted on, and rotated at a comparatively high rate of speed by, a power driven shaft 7. As well understood in the art, the wheel is adapted during drive thereof and when a metallic or other surface is placed against its periphery to polish or buff the surface. A hub structure 8 serves as a medium for operatively or drivably connecting the buffing wheel to the shaft. The wheel surrounds the hub structure and consists of a rectilinear series of side by side buffing sections 9. As shown in Figure 1 of the drawings the hub structure embodies a pair of spaced apart discs 10 and 11 and a plurality of bolts 12. The disc 10 is centrally apertured and surrounds the shaft 7. It is disposed inwards of the outer end of the shaft and abuts against an annular shoulder 13. The other disc, i. e., the disc 11, is centrally apertured and surrounds the outer end of the shaft 7. Said outer end of the shaft is provided with a screw thread 14 and has thereon a nut 15 which, when tightened, clamps the hub structure 8 as a whole to the shaft. The bolts 12 of the hub structure are preferably three in number and comprise shanks 16 having heads 17 at certain ends thereof and nuts 18 at their other ends. They are arranged in parallel relation with the shafts 7 and extend through aligned holes 19 in the outer marginal portions of the discs 10 and 11. The heads 17 of the bolts abut against the outer surface of the disc 10 and the nuts 18 abut against the outer surface of the disc 11. When the nuts 18 are tightened the discs 10 and 11 are drawn towards one another into clamped relation with the buffing sections 9. Preferably the bolts 12 are spaced equidistantly apart. As shown in Figure 1, the discs 10 and 11 have apertures 20 therein in order to permit air to enter the interior of the hub structure 8.

The buffing sections 9 when in operative relation with the hub structure surround the shanks 16 of the bolts 12 and are clamped between the outer marginal portions of the discs 10 and 11 as heretofore indicated. Each of the buffing sections 9 consists of a plurality of annular juxtaposed fabric layers 21 and a core. The inner margins of the fabric layers are pleated or gathered and are connected together by stitching 22. Preferably the layers 21 of each buffing section are formed by gathering or pleating one side marginal portion of a fabric strip and then winding or wrapping the strip in a spiral fashion. The gathering or pleating of the inner marginal portions of the fabric layers 21 forms radially extending air passages which in connection with drive or operation of the wheel provide for ventilation or air circulation for cooling purposes. The cores of the sections serve to hold the fabric layers 21 together and support them with respect to the hub structure 8. They fit within and serve to clamp together the inner marginal portions of the fabric layers. The core of each buffing section 10 consists of a pair of complementary pre-formed oppositely positioned rigid rings 23 and 24. The latter are formed of metallic stampings. The metal stock of which the rings 23 and 24 are formed is preferably of 20 gauge in order that the rings have the desired rigidity. The rings 23 consist of cylindrical base flanges 25, outer side flanges 26 and teeth 27. The outer side flanges 26 of the rings 23 project outwards

at right angles from the cylindrical base flanges 25 and when the cores are in their assembled position engage or abut against the inner marginal portions of certain of the outer-most fabric layers 21. The teeth 27 of each of the rings 23 are arranged in a circular series and are spaced equidistantly apart. As shown in the drawings, the teeth 27 of the rings 23 are joined to the outer marginal portions of the outer side flanges 26. They extend at right angles to the side flanges and extend in the same direction as the cylindrical base flanges 25. When the cores are in assembled relation with the fabric layers 21, the teeth 27 are embedded in the inner marginal portions of certain of the fabric layers, as best shown in Figure 6. Each of the rings 24 of the cores consists of a cylindrical base flange 28, an annular outer side flange 29, teeth 30 and an annular lip 31. The cylindrical base flanges 28 of the rings 24 are slightly wider than the base flanges 25 of the rings 23 and have the external diameter thereof the same as the internal diameter of the cylindrical base flanges 25. They fit within, and are in telescopic relation with, the cylindrical base flanges 25 and grip the latter frictionally when the cores are in their assembled position. The inner and outer peripheries of the base flanges 28 are smooth. The cylindrical base flanges 28 are of such internal diameter that when the buffing sections 9 are mounted on the hub structure 8 they engage the shanks 16 of the bolts 12. The annular outer side flanges 29 of the rings 24 project outwards at right angles from the cylindrical base flanges 28 and are disposed in opposed relation with the annular outer side flanges 26. They are in rigid relation with the cylindrical base flanges 28 and lap or abut against the inner marginal portions of the adjacent fabric layers 21. The teeth 30 of each of the rings 24 are arranged in a circular series and are spaced equidistantly apart. They extend at right angles to the annular outer side flanges 29 and project in the same direction as the cylindrical base flanges 28. As shown in the drawings, the teeth 30 are arranged in alternate or interfitting relation with the teeth 27 and when the cores are in their assembled position, extend through or penetrate the inner marginal portions of certain of the fabric layers 21. The teeth 30 and 27 are of such length that the inner marginal portions of all of the fabric strips 21 are gripped or penetrated. The annular lips 31 are connected to the free margins of, and project outwards at right angles from, the cylindrical base flanges 28 of the rings 24 and are arranged in lapped relation with the inner marginal portions of the annular outer side flanges 26 of the rings 23. They have a twofold purpose in that they serve positively to prevent spreading or separation of the rings 23 and 24 when the cores are fully assembled and also function to space the side flanges 26 of the rings 23 from the side flanges 29 of the rings 24. As shown in Figure 1, the buffing sections 9 are similarly positioned or arranged to the end that there is but one lip 31 between two adjoining buffing sections. Before assembling the rings 23 and 24 constituting the cores of the buffing sections the lips 31, instead of extending outwards, extend in coaxial relation with the base flanges 28, as shown in Figure 4. In connection with assembly of the buffing sections 9 the fabric layers 21 and the core forming rings 23 and 24 are positioned as shown in Figure 4. Thereafter the rings are shifted together by way of a punch press or other suitable

means in order to bring them into clamped or gripping relation with the inner marginal portions of the fabric layers 21. In connection with shifting together of the rings 23 and 24 the cylindrical base flanges 28 of the rings 24 slide into telescopic and gripping relation with the base flanges 25 of the rings 23. In addition, the teeth 30 and 27 are brought into penetrating relation with the inner portions of the fabric layers 21. After shifting together of the rings 23 and 24 into the position shown in Figure 5 the lips 31 are bent outwards into lapped relation with the inner marginal portions of the side flanges 26 of the rings 23 in order positively to lock the rings against separation. Outward bending of the lips 31 is accomplished or effected by means of any well known metal bending or rolling machine. As shown in the drawings the width of the lips is approximately one-third that of the annular side flanges of the core forming rings. After the lips are bent into lapped relation with the side flanges 26 they serve positively or permanently to lock the rings against separation in response to the outward pressure that is exerted by the pleated inner margins of the fabric layers 21 due to compression.

In order to permit air to flow from the interior of the hollow hub structure 8 outwards past and between the fabric layers 21 for purposes of cooling the layers in connection with use of the buffing wheel each of the lips 31 is provided with an annular series of notches 32. The latter are spaced equidistantly apart, as shown in Figure 2, and extend throughout the full width of each lip. The notches 32 facilitate outward bending of the lips in addition to providing for the outflow of cooling air past the fabric layers 21. In connection with use of the buffing wheel air is drawn into the interior of the hollow hub structure 8 via the apertures 20 and then in response to the action of centrifugal force flows outwards through the notches 32 and then between the fabric layers of the buffing sections 9. As the result of outflow of air between and past the fabric layers 21 cooling of the layers takes place with the result that the wheel as a whole does not overheat.

When it is desired to assemble the buffing wheel on the hub structure 8 the disc 11 is removed from the outer end of the shaft 7 after removal of the nut 15 and the nuts 18. After removal of the disc 11 the buffing sections 9, while arranged in rectilinear series and side by side relationship, are slid onto the shanks 16 of the bolts 12. After sliding of the buffing sections 9 into place the disc 11 is mounted on the outer end of the shaft and is secured in place by application and tightening of the nut 15 and the nuts 18. When such nuts are tightened the outer marginal portions of the discs 10 and 11 are in clamped relation with the cores of the buffing sections and serve to hold the sections in place. The shanks of the bolts 12 serve to hold the buffing sections 9 against radial displacement with respect to the shaft. After assembly of the buffing wheel as hereinbefore indicated, the hub structure 8 serves to connect the buffing sections 9 for drive by the shaft 7.

The herein described buffing wheel is essentially simple in design or construction and may be manufactured or fabricated at a comparatively low cost. It may be built up to any desired length by adding additional buffing sections and is characterized by the fact that the rigid, outwardly extending annular lips 31 on the free margins of the base flanges 28 of the rings 24 positively lock the core forming rings against

5 separation and so space apart the buffing sections that the notches 32 permit a sufficient outflow of air between and past the fabric layers 21 to effect efficient cooling of the wheel as a whole.

The invention is not to be understood as restricted to the details set forth since these may be modified within the scope of the appended claims without departing from the spirit and scope of the invention.

Having thus described the invention, what I claim as new and desire to secure by Letters Patent is:

1. As a new article of manufacture, a section 15 adapted in conjunction with like sections and a hub structure to form a buffing wheel and comprising a plurality of annular juxtaposed fabric layers and a core extending around and serving to secure together the inner marginal portions of the layers and embodying a pre-formed rigid one-piece ring consisting of a cylindrical base flange, an annular outer side flange extending outwards from the outer margin of the base flange and arranged in lapped relation with the inner marginal portion of one of the outer-most fabric layers, and a circular series of spaced apart teeth connected to the outer margin of the outer side flange, projecting in the same direction as the base flange and embedded in the inner marginal portions of certain of the fabric layers, and a complemental pre-formed rigid one-piece ring positioned reversely with respect to the first mentioned ring and consisting of a cylindrical base flange fitting within the base flange of said first mentioned ring, an outer annular side flange extending outwards from the outer margin of the base flange of the complemental ring and arranged in lapped relation with the inner marginal portion of the other outermost fabric layer, a circular series of spaced apart teeth connected to the outer margin of the last mentioned side flange, projecting in the same direction as the first mentioned teeth and embedded in the inner marginal portions of certain of the fabric layers, and a lip connected to, and extending outwards from, the free margin of the base flange of said complemental ring, arranged in lapped relation with the outer side flange of said first mentioned ring, and serving to hold the two rings against separation.
2. As a new article of manufacture, a section 30 adapted in conjunction with like sections and a hub structure to form a buffing wheel and comprising a plurality of annular juxtaposed fabric layers and a core extending around and serving to secure together the inner marginal portions of the layers and embodying a pre-formed rigid one-piece ring consisting of a cylindrical base flange, an annular outer side flange extending outwards from the outer margin of the base flange and arranged in lapped relation with the inner marginal portion of one of the outer-most fabric layers, and a circular series of spaced apart teeth connected to the outer margin of the outer side flange, projecting in the same direction as the base flange and embedded in the inner marginal portions of certain of the fabric layers, and a complemental pre-formed rigid one-piece ring positioned reversely with respect to the first mentioned ring and consisting of a cylindrical base flange fitting within the base flange of said first mentioned ring, an outer annular side flange extending outwards from the outer margin of the base flange of the complemental ring and arranged in lapped relation with the inner marginal portion of the other outermost fabric layer, a circular series of spaced apart teeth connected to the outer margin of the last mentioned side flange, projecting in the same direction as the first mentioned teeth and embedded in the inner marginal portions of certain of the fabric layers, and a lip connected to, and extending outwards from, the free margin of the base flange of said complemental ring, arranged in lapped relation with the outer side flange of said first mentioned ring, and serving to hold the two rings against separation.

the inner marginal portion of the other outermost fabric layer, a circular series of spaced apart teeth connected to the outer margin of the last mentioned side flange, projecting in the same direction as the first mentioned teeth and embedded in the inner marginal portions of certain of the fabric layers, and an annular lip connected to, and extending outwards from, the free margin of the base flange of said complementary ring, arranged in lapped relation with the outer side flange of said first mentioned ring, serving to hold the two rings against separation, and having formed therein full width notches for permitting air to flow from within the core outwards past the fabric layers.
